Primary Examiner — Janice Patyk*Assistant Examiner* — Kendra L Hebel(74) *Attorney, Agent, or Firm* — Akerman LLP(57) **CLAIM**

The ornamental design for a handle for cookware, as shown and described.

DESCRIPTION

FIG. 1 is a perspective view of a handle for cookware, showing my new design;

FIG. 2 is a side view thereof;

FIG. 3 is a top view thereof;

FIG. 4 is a bottom view thereof;

FIG. 5 is a front view thereof;

FIG. 6 is a back view thereof; and,

FIG. 7 is a cross-section view thereof, taken along line 7-7 in FIG. 3.

The broken lines showing portions of the article form no part of the claimed design.
